UNITED STATES PATENT OFFICE.

ALBERT POLASCHECK, OF THIENSVILLE, WISCONSIN.

CONTAINER.

Application filed November 26, 1928. Serial No. 821,916.

This invention relates to containers.

Objects of this invention are to provide a novel form of container which is provided with a removable top, equipped with means for interlocking with the neck of the container so as to force the top upon a gasket, said interlocking means being formed of non-friable members, adapted to slide within a cam-like slot to draw the cap or top down upon the neck and to provide these interlocking means with independent adjustable elements, so that they may, themselves, be adjusted as required.

An embodiment of the invention is shown in the accompanying drawings, in which:

Figure 1 is a sectional view through the upper portion of a container.

Figure 2 is a transverse sectional view on the line 2—2 of Figure 1.

Figure 3 is a fragmentary detailed section on the line 3—3 of Figure 1.

Figure 4 is a side elevation of the upper portion of a container.

Referring to the drawings, it will be seen that the container comprises a body portion 1, which has a contracted neck provided with oppositely positioned cam grooves 2. These grooves slant downwardly, as shown in Figure 4, and are provided with entrance slots 3.

Further, the container is provided with an outer lip 5 which is spaced from the upper face of the neck, a gasket 6 of yielding material is carried on the upper face of the neck and is fitted beneath the outwardly-turned neck 5. The top 7 is preferably formed of glass and is provided with a down-turned bottom bead 8 which is adapted to bear against the gasket when the device is locked in place. The top is provided with a downwardly extending peripheral flange 9, as shown in Figure 1, and is provided with apertures for the reception of the stems 10 of bolts. These bolts each terminate an integrally formed bottom member having one

arm projecting inwardly and indicated by the reference character 11, and having another arm projecting outwardly, terminating in an upwardly-turned angularly position on lip 12, which is positioned on the outer side of the peripheral flange 9 of the top. This construction prevents the locking members from turning when the jar top is turned with reference to the container. The inwardly projecting ears 11 of the interlocking members are adapted to enter the openings 3 of the grooves 2, and when the cap is turned,

the members slide down these cam grooves and draw the cap into binding engagement with the gasket.

Further, it is to be noted that the members 10 are independently adjustable, as they are each provided with nuts 13 which may be tightened as required. They are shown drawn up against the bottom edge of the peripheral flange 9, but they may occupy any relative position thereto, so that the exact tensioning of the cap, or pressure exerted by the cap, may be adjusted by tightening the bolts.

The top is preferably provided with upstanding lugs 14, which are used when screwing or turning the top during the locking operation.

It is apparent from an inspection of Figure 1 that as the top has been turned, as required, that any individual fastener may be tightened if desired. They are shown drawn up into their tightest position in Figure 1.

It is to be noted particularly, that the fasteners or interlocking members which engage with the grooves 2 are of metal and will not, therefore, readily break or chip. They distribute the strain to the glass top and prevent localization of the strain upon any lip of the glass top, as has heretofore been the case.

Further, it is to be noted that the top and body portion may be both made of glass if desired, or any other material, or if desired, the top may be made of glass and the body of some other material.

It will be seen further that the construction is very simple, is easy to produce, and provides an effective lock construction for containers.

Although the invention has been described in considerable detail, such description is intended as illustrative rather than limiting, as the invention may be variously embodied and as the scope of such invention is to be determined as claimed.

I claim:

1. The combination of a container having a neck provided with cam grooves, a cover cooperating with said neck and provided with independently, adjustable fasteners, having projecting ears adapted to fit within said cam grooves.

2. The combination of a container having a neck provided with opposed cam grooves slanting downwardly at their inner ends and having open, upwardly extending mouths, a cover for said container, having a down-

wardly extending bead, a gasket interposed between said bead and the upper face of the neck of the container, and a plurality of fasteners having bolt-like stems passing through 5 the cap and provided with adjusting nuts, said fasteners each having an inwardly projecting lip adapted to enter one of said grooves.

3. The combination of a container having 10 a neck provided with opposed cam grooves slanting downwardly at their inner ends and having open, upwardly extending mouths, a cover for said container, having a downwardly extending bead, a gasket interposed between 15 said bead and the upper face of the neck of the container, and a plurality of fasteners having bolt-like stems passing through the cap and provided with adjusting nuts, said fasteners each having an inwardly projecting lip adapted to enter one of said 20 grooves, said fasteners each having an outwardly projecting arm provided with an up-

turned lip, and said cap having a peripheral flange interposed between the stem of the fasteners and the up-turned lip. 25

4. A container comprising a neck terminating with a mouth having an annular shoulder, a gasket seated thereon, inclined grooves in the neck provided with abrupt terminal channels intersecting the shoulder; the combination of 30 a cap therefor, having an annular flange adapted to fit over the container neck and provided with apertures, adjustable bolts mounted in the apertures having heads provided with inwardly extending lugs for engagement with the neck channels and grooves, the bolt heads being also provided with lips for engagement with the cap flanges. 35

In testimony that I claim the foregoing I have hereunto set my hand at Milwaukee, in 40 the county of Milwaukee and State of Wisconsin.

ALBERT POLASCHECK.
